GARMENT

Doré Reichenbaum, Milwaukee, Wis.

Application February 13, 1932. Serial No. 592,761

7 Claims. (Cl. 2—228)

This invention relates to garments and refers more particularly to riding breeches.

As is well known, riding breeches, extend down below the knee of the wearer to be received in the tops of the boots, and to hold them down in the boots, it is necessary to fit the lower leg portions snugly to the calf. But as the leg portions of the breeches must be passed over the feet and calves, a snug fit cannot be obtained 10 without slitting the same upwardly a distance from the bottom.

Heretofore it has been customary to provide either buttons or laces for closing the slits. Where buttons were used there was always untidy gapping between the buttons, button holes to wear out and buttons to come off; and where laces were used, there were eyelet rings to pull out or hand made eyelet holes to fringe. Moreover in both cases, closing the slits was always 20 a tedious slow task.

With these and other objectionable features of existing breech construction in mind this invention has as one of its objects to provide a simple but effective construction for the leg portions of riding breeches and similar garments, in which the required leg opening is obtained 25 with a slit of minimum length and a novel flap arrangement provides an adjustable closure which entirely obviates objectionable buttons and 30 lacings.

Another object of this invention resides in the provision of substantially stiff ribs sewed into the leg portions directly beneath the knee to assist in holding the same down into the boot 35 and to preclude objectionable wrinkling.

With the above and other objects in view which will appear as the description proceeds, this invention resides in the novel construction, combination and arrangement of parts substantially 40 as hereinafter described and more particularly defined by the appended claims, it being understood that such changes in the precise embodiment of the hereindisclosed invention may be made as come within the scope of the claims.

45 In the accompanying drawing, one complete example of the physical embodiment of this invention is illustrated constructed according to the best mode so far devised for the practical application of the principles thereof, and in 50 which:

Figure 1 is a perspective front view of a pair of breeches embodying this invention; and

55 Figure 2 is a detail perspective view illustrating the specific construction of the lower leg portion.

Referring now more particularly to the accompanying drawing, the numeral 5 designates a pair of riding breeches having leg portions 6, the lower ends 7 of which extend down beneath the knee to be received in the tops of the boots 60 usually worn with attire of this character.

Each lower leg portion has an inner panel 8 and an outer panel 9 sewed together by a seam 10 which is located just to the inside of the front of the leg. The upper portion of the inner 65 panel may be reinforced by a piece of leather 11 sewed thereto as is customary.

The seam 10 connecting the inner and outer panels 8 and 9 terminates at a point 12 which is spaced a few inches from the extreme bottom 70 of the leg portion. Beneath the end of the seam the adjacent portions of the panels 8 and 9 are left unconnected to provide a slit which increases the effective opening of the leg portion to facilitate the passage of the foot and calf there- 75 through.

It is observed that the marginal edge of the outer panel 9 extends straight down to its bottom in line with the seam 10, but that the inner panel 8, beneath the end of the seam 12, is extended 80 to form a flap 13 which is adapted to overlie the adjacent portion of the outer panel 9.

Sewed to the extreme bottom of both panels is a continuous cloth band or tape 14, the ends 15 and 16 of which extend respectively beyond the marginal edge of the outer panel 9 and the extreme end of the flap 13 to be tied together as at 17. The end 15 is adapted to pass through an opening 18 formed in the inner panel 8 adjacent the base of the flap 13 and the end 16 is sufficiently 90 long to encircle the calf of the wearer. In this manner, the extreme bottom of the leg portion is adjustable to the calf of the wearer and may be drawn snugly thereabout to hold the leg portion 95 down in the boot.

Above the termination of the seam 10 a pocket 19 is formed to receive a stay of whalebone or other suitable material 20. This stay serves to keep the portion directly beneath the knee tidy and glove fitting, and inasmuch as the breech has a tight fit at the knee, the presence of stays in preventing curling or wrinkling assists in holding the leg portion down in the boot. In other words, the tight fit at the knee holds the breech against creeping up at this point. Consequently, upward shifting of that portion beneath the knee would be possible only if lateral wrinkling or curling were permitted. The stays prevent such wrinkling and thus have a definite part in holding the leg portions down.

From the foregoing description taken in connection with the accompanying drawing, it will be readily apparent to those skilled in the art to which an invention of this character appertains, that this invention provides novel means for holding the lower leg portions of riding breeches and similar garments down into the boots of the wearer without necessitating objectionable buttons, lacings, or similar fastening means; and that a more convenient, more serviceable riding breech is obtained at less cost and without sacrificing any cardinal point of comfort or service to the equestrian.

It is also apparent that the novel construction of this invention requires less material than the conventional type of breech and that due to the novel panel design, adjustments and alterations can be made with minimum effort and cost.

What I claim as my invention is:

1. In a garment, a leg portion large enough to be passed over the foot and calf of a wearer and sloping downwardly from a wide upper portion to a narrow tight fitting knee portion, means connected with the lower leg portion and extending downwardly from the knee portion to prevent wrinkling and thereby hold the same down.

2. In a garment, a leg portion large enough to be passed over the foot and calf of the wearer and sloping downwardly from a wide upper portion to a narrow tight fitting knee portion, and a substantially stiff rib extending downwardly from the knee portion to prevent wrinkling and thereby hold the lower leg portion down in proper position.

3. In a garment, a leg portion large enough to be passed over the foot and calf of a wearer and to have a tight fit at the knee, a substantially stiff rib sewed into the lower leg portion to be disposed beneath the knee of the wearer to prevent wrinkling and thereby hold the lower leg portion down in proper position, and tie straps connected with the bottom of the lower leg portion for securing the same snugly about the calf of the wearer to cooperate with the rib in holding the leg portion down in proper position.

4. In a garment, a leg portion large enough to be passed over the foot and calf of a wearer and to have a tight fit at the knee, a substantially stiff rib extending substantially longitudinally of the leg portion adjacent the lower end thereof and spaced from the extreme bottom to be positioned beneath the knee of the wearer to prevent wrinkling and thereby hold the lower leg portion down in proper position, the lower leg portion being provided with a slit beneath the substantially stiff rib, and a flexible band connected with the extreme bottom of the lower leg portion and having its ends extending beyond the marginal edge portion of the slit to provide ties for drawing the extreme bottom of the lower leg portion snugly about the calf of the wearer.

5. In a garment, a leg portion large enough to be passed over the foot and calf of a wearer and

to have a snug fit at the knee, a substantially stiff rib extending substantially longitudinally of the leg portion adjacent the lower end thereof and spaced from the extreme bottom to be positioned beneath the knee of the wearer to prevent wrinkling and thereby hold the lower leg portion down in proper position, the lower leg portion being provided with a slit beneath the substantially stiff rib, a flap forming one side of the slit and adapted to overlie the other side, and a flexible band connected with the extreme bottom of the lower leg portion and having its ends extending beyond the marginal edges of the slit to provide ties for drawing the bottom of the lower leg portion snugly about the calf of the wearer, one end of said band extending through an opening adjacent the flap whereby said end overlies the bottom of the lower leg portion as it encircles the calf of the wearer.

6. In a garment of the character described, a leg portion including adjacent panels extending to the bottom of the leg portion, a seam connecting the adjacent marginal edges of the panels to a point spaced from the bottom of the leg portion and below the knee portion, said knee portion having a snug fit on the knee of a wearer, the marginal edge portion of one panel beneath the termination of the seam extending in a straight line, a flap on the other panel adapted to overlie said extended marginal edge portion of the first mentioned panel with the bottom edges of the flap and both panels substantially on a common plane, and a tape fixed to the extreme bottom of the leg portion and having its ends extending beyond the marginal edge of the first mentioned panel and the flap on the other panel to afford tie means for drawing the flap over the first mentioned panel and about the calf of the wearer, the end portion of the tape extended beyond the marginal edge of the first mentioned panel passing through an opening in the second mentioned panel whereby the flap overlies the first mentioned panel without wrinkling.

7. In a garment of the character described, a leg portion open at its bottom and having a slit extending upwardly from its bottom to augment the effective opening of the bottom and to enable the foot and calf of the wearer to be passed therethrough, said leg portion having a snug fit at the knee and the slit terminating at a point adjacent the wide part of the calf of the wearer, a substantially stiff rib extending longitudinally of the leg portion between the termination of the slit and the knee portion to hold the leg portion directly beneath the knee against wrinkling and thereby hold the same down in proper position, a flap at one side of the slit and adapted to overlie the other side, and a flexible band connected with the extreme bottom edge of the leg portion and having its ends extended to form ties for drawing the flap over said other side of the slit into snug engagement with the calf of the wearer.

DORÉ REICHENBAUM.
